Primary Examiner — Marcus A Jackson(74) *Attorney, Agent, or Firm* — Prakash Nama; Global IP Services, PLLC(57) **CLAIM**

The ornamental design for a LED stadium light, as shown and described.

DESCRIPTION

FIG. 1 is a front elevational view of a LED stadium light showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a rear perspective view thereof;

FIG. 8 is a bottom perspective view thereof; and,

FIG. 9 is a front perspective view thereof.

The broken lines illustrating portions of the LED stadium light do not form part of the claimed design.
